RAIL SPIKE

Harry A. Lacerda, Los Angeles, Calif., assignor of
one-half to Matthew G. Eggett, Trona, Calif.

Application February 1, 1950; Serial No. 141,720

2 Claims. (Cl. 85—21)

1

This invention is concerned with a nail or spike, and is particularly practical as applied to a spike for use in securing a rail to a tie, and it is a general object of the invention to provide a simple, practical, dependable device of this general character.

It is common to construct tracks for trains by providing rails mounted on cross ties which are formed of wood. The rails are steel and are provided with mounting flanges which rest on bearing plates which, in turn, rest on the ties. It is common, in fact, practically universal to employ spikes for securing rails to ties, and in the conventional case the spikes are entered through openings in the tie plates and are driven into the ties. The heads on the spikes overlie the flanges of the rails and the action of the spikes is to retain the rails on the ties and against spreading.

The usual railroad spike is difficult or hard to drive and after being in service but a short time the ordinary spike is usually loose or partially withdrawn from the tie due to the working action that occurs as the rail deflects under the load of rolling stock such as locomotives and cars and/or due to expansion and contraction of the wood fibres. Attempts to secure or anchor spikes as by providing them with burrs or like rough features generally prove unsatisfactory as they result in chewing or tearing of the ties and, consequently, do more harm than good. Further, after the usual spike has been in service an appreciable length of time it works in the hole established in the tie, tending to enlarge the hole, and in many cases the spike becomes corroded, particularly at its upper end portion or close beneath the head, as where it passes through the plate and into the tie, all with the result that its efficiency or efficacy is materially decreased.

The rail spike provided by this invention conforms, generally, in its major features with the usual spike in that it has an elongate body rectangular in cross sectional configuration and it has an integral head at one end with a projecting part for engaging the flange of a rail and is sharpened at the other end to readily enter the wood of a tie. Being thus constructed the spike of the present invention is useful with equipment such as is now in general use, that is, with usual rails, plates and ties, and it can be handled, that is, both driven and withdrawn, by tools and methods employed to handle ordinary spikes.

The present invention provides anchoring means that serves to effectively maintain the

spike in position after it has been driven into place and which serves to minimize the force necessary to effect proper driving of the spike into operating position. In its preferred form the invention provides channels in the several sides of the body of the spike and each channel is inwardly convergent or has inwardly convergent walls. The several channels are preferably straight and the channels at each side of the body are in a series with adjacent channels pitched or inclined in opposite directions and with the ends of such channels joined at corners of the body where the body is notched somewhat. The notches occurring at the edges of the body are common to the channels at the sides adjacent the corners. The structure as thus provided allows for free circulation of fluids as, for instance, air or sap, lengthwise of the body as the spike is driven, and provides for a limited amount of swelling of the wood of the tie into the spike, all without so tearing or injuring of the wood as to weaken or destroy it.

It is a general object of this invention to provide a spike of the general character referred to which is so channeled at its several sides as to provide for the free flow or circulation of fluids such as air or sap, with the result that the spike can be driven easily, even into hard wood such as may be employed in railroad ties. It is a further object of this invention to provide a spike construction of the general character referred to which will remain firmly in place when once driven into rail holding position, and it does not back or work out when subject to the usual action that occurs as the retained rail is deflected due to the passage of rolling stock over the rail.

Another object of this invention is to provide a spike of the general character referred to having a surface such as to resist corrosion such as usually occurs in the case of the ordinary railroad spike.

A further object of this invention is to provide a spike of the general character referred to in which the sides of the body are channeled so that the spike is effectively retained or locked in place while at the same time there is a total absence of undesirable burrs or projections likely to injure or tear a tie.

The various objects and features of my invention will be fully understood from the following detailed description of a typical preferred form and application of the invention, throughout which description reference is made to the accompanying drawings, in which:

Fig. 1 is a side elevation of a portion of a typi-

cal unit of rolling stock such as a box-car, showing the truck of the car on a conventional rail supported on cross ties of wood through plates and held on the ties by spikes engaged through the plates so their heads engage the flange of the rail. Fig. 2 is an enlarged transverse sectional view of a rail showing it resting on a tie and showing a spike provided by the present invention being driven through the plate which is between the rail and tie in the course of being introduced into position to retain the rail on the tie. Fig. 3 is a detailed sectional view similar to Fig. 2 showing the spikes in operating position retaining the rail in place and showing a wheel on the rail, the view being taken substantially as indicated by line 3-3 on Fig. 2. Fig. 4 is an enlarged perspective view of the spike provided by the present invention. Fig. 5 is an enlarged detailed transverse sectional view of the spike taken substantially as indicated by line 5-5 on Fig. 4. Fig. 6 is an enlarged view of a portion of the structure, being a view taken as indicated by line 6-6 on Fig. 5 and illustrating the manner in which wood of a tie expands or enters into the corner notch of the spike to effectively retain the spike in place. Fig. 7 is a view similar to Fig. 6 being taken as indicated by line 7-7 on Fig. 4, and Fig. 8 is an enlarged sectional view of an ordinary or conventional railroad spike in a corroded condition and loose in a tie and loosely carrying a rail, all as is frequently the case when an ordinary spike has been in use for an appreciable length of time.

The spike provided by this invention, being a so-called railroad spike, is intended primarily for use for securing a railroad rail A to a typical tie B and in the usual case such a rail is supported on the tie B through a plate C. In the drawings I have shown an ordinary or conventional rail A with a head or tread 10 supported on a vertical web 11 which projects upwardly from a base which is formed by laterally projecting flanges 12. The head 10 of the rail carries the wheels 13 of trucks D provided on rolling stock such as locomotives and cars of various types or classes. In the drawings I have illustrated a portion of a box car E and have shown one truck of the car with its wheels on a rail, the wheels being the usual flanged wheels commonly found on railroad rolling stock.

The spike provided by this invention and as illustrated in Figs. 1 to 7 of the drawings, involves, generally, an elongate body F sharpened at one end to readily enter a tie B and provided at its other end with a head H.

The body F of the spike is preferably made to conform generally with standards established for ordinary railroad spikes, that is, it is about the size and shape of an ordinary spike and the head H is formed on the upper end of the spike to be integral therewith, as is the case in an ordinary spike. The body in such case is preferably of substantial length and is substantially uniform in cross sectional configuration from one end to the other, except at its lower end portion where it is sharpened or pointed, as will be hereinafter described. The particular spike illustrated is rectangular in cross sectional configuration and is shaped or dressed at its lower end to readily enter a tie. The lower end portion of the spike is shown having opposite sides 15 made convergent so that they join to establish an edge or sharp end 16 that will readily enter the wood of a usual tie B.

The head H which is preferably integral with

75

the body has a laterally projecting lip portion 18 with an inclined lower side 19 to engage over the edge portion of a rail flange 12.

The anchoring means as provided by the present invention involves a plurality of like channels 20 in each of the several sides 21 of the body F and in accordance with the preferred form of the invention there are channels 20 in each of the several sides 21 of the body. The channels at or in each side 21 of the body F may be substantially alike as to arrangement and relationship and it is preferred that the several channels 20 in each side 21 be arranged and related so as to be in a series extending lengthwise of the body. Each individual channel 20 is preferably straight from one end to the other and adjacent channels are inclined or pitched oppositely to each extends somewhat lengthwise of the body as it extends across the body from one edge or corner 22 to the other. Adjacent channels 20 preferably connect or come together at openings or notches 23 provided in the corners 22 that occur where the side 21 terminates. Through this general arrangement and relationship of features, all of which is clearly illustrated in Fig. 4 of the drawings, the channels on or in each side 21 of the spike body F form a substantially zig-zag pattern.

Each individual channel 20 is preferably in the form of a simple, straight, groove having inwardly convergent walls 30 and the edges 31 where the walls 30 join the side 21 are preferably rounded, or finished slightly so that there are no sharp edges exposed to the tie. In practice I prefer to make each channel of such width and depth that a portion of the tie will bulge somewhat into the channel as shown at X in Fig. 7. In like manner the notches 23 provided in the corners are such that portions Y of the tie will bulge into them, as shown in Fig. 6.

In accordance with the present invention the series of channels 20 provided in adjacent sides 21 of the body F are so related that they all terminate at the notches 23 so that each notch is common to four channels, as will be apparent from consideration of Fig. 4 of the drawings, this being true except at the ends of the series of notches where the end notches may have less than four channels joined therewith.

In accordance with the invention the body and head of the spike are preferably formed of a ferrous metal such as a suitable steel and the entire spike is covered by a protective coating, preferably a coating of non-corrosive or corrosion resistant metal. In practice where a steel spike is provided the coating may be cadmium or the like, applied to the steel by plating. It is to be understood that the entire spike including the body and the head, may be formed of corrosion resistant metal.

With the construction provided by the present invention the spike can be driven into place in the usual manner using the usual hammer or sledge S as shown in Fig. 2, and I have found that by my channeled body construction the spike provides for ready or free circulation of air or sap that may be present, allowing the spike to readily enter the tie. When once in place in a tie the portions X and Y that bulge into the channels and notches provided in the body of the spike effectively retain the spike in the tie and the spike will remain in place over an extended period of time, even when subjected to the working that occurs as rolling stock deflects the rail and causes working of the tie in the road bed,

which road bed in time becomes so packed that the tie works up and down as the rolling stock passes over the rail. The channels and notches as provided by the present invention, being formed and related as above described, retain the body of the spike without biting into the wood or fibers of the tie in such manner as to weaken or destroy the tie, and consequently the spike can be used without danger of injury to the tie.

Having described only a typical preferred form and application of my invention, I do not wish to be limited or restricted to the specific details herein set forth, but wish to reserve to myself any variations or modifications that may appear to those skilled in the art and fall within the scope of the following claims:

Having described my invention, I claim:

1. A spike of the character described including, an elongate body with a pointed portion at one end and of substantially uniform size and shape throughout its length except at said pointed portion, and a head on the other end of the body, the body being substantially rectangular in cross sectional configuration and having flat sides each with a series of grooves extending longitudinally of the body and forming a zigzagged channel extending substantially throughout the uniform portion, the grooves having walls joined to the said sides by rounded corners, adjacent grooves of each series being oppositely inclined longitudinally of the body and connected together only at their ends which occur at the corners of the body, there being notches in the corners of the body where the channels are connected together, the notches in each corner being common to the channels in the sides adjacent the corner, said sides having flat smooth uninterrupted surfaces between the grooves, the combined areas of the said surfaces being substantially greater than the combined areas occupied by the grooves.

2. A spike of the character described including, an elongate body with a pointed portion at one end and of substantially uniform size and shape throughout its length except at said pointed por-

tion, and a head on the other end of the body, the body being substantially rectangular in cross sectional configuration and having flat sides each with a series of grooves extending longitudinally of the body and forming a zigzagged channel extending substantially throughout the uniform portion, the grooves having walls joined to the said sides by rounded corners, adjacent grooves of each series being oppositely inclined longitudinally of the body and connected together only at their ends which occur at the corners of the body, there being notches in the corners of the body where the channels are connected together, the notches in each corner being common to the channels in the sides adjacent the corner, said sides having flat smooth uninterrupted surfaces between the grooves, the combined areas of the said surfaces being substantially greater than the combined areas occupied by the grooves.

HARRY A. LACERDA.
